(57) **CLAIM**

The ornamental design for a display panel or portion thereof with animated graphical user interface, as shown and described.

DESCRIPTION

FIG. 1 is a front view of a first image of a display panel or portion thereof with animated graphical user interface; FIG. 2 is a front view of a second image thereof; FIG. 3 is a front view of a third image thereof; FIG. 4 is a front view of a fourth image thereof; FIG. 5 is a front view of a fifth image thereof; FIG. 6 is a rear view of the display panel of FIG. 1; FIG. 7 is a side view of the display panel; FIG. 8 is another side view of the display panel; FIG. 9 is a top view of the display panel; and, FIG. 10 is a bottom view of the display panel.

The broken lines in the drawings showing the display panel or portion thereof form no part of the claimed design. The appearance of the image transitions sequentially between the images shown in FIGS. 1-5. The process or period in which an image transitions to another forms no part of the claimed design.
